(57) **CLAIM**

The ornamental design for a streetlight, as shown and described.

DESCRIPTION

FIG. 1 is a perspective view of a streetlight showing my new design;

FIG. 2 is a front view thereof, the rear view being a mirror image of the front view;

FIG. 3 is a left side view thereof;

FIG. 4 is a right side view thereof;

FIG. 5 is a top view thereof;

FIG. 6 is a bottom view thereof; and,

FIG. 7 is another perspective view thereof.

The broken line portions of the figure drawings are for illustrative purposes only and form no part of the claimed design.
